UNITED STATES PATENT OFFICE.

FRANK A. FALK, OF STACYVILLE, IOWA.

LEVER MECHANISM.

No. 874,175.

Specification of Letters Patent.

Patented Dec. 17, 1907.

Application filed May 23, 1907. Serial No. 375,217.

To all whom it may concern:

Be it known that I, FRANK A. FALK, residing at Stacyville, in the county of Mitchell and State of Iowa, have invented certain new and useful Improvements in Lever Mechanisms, of which the following is a specification, reference being had to the accompanying drawings.

My invention relates to improvements in lever mechanisms and particularly to lever mechanisms in which the position of the lever is controlled by the engagement of pawls between the teeth of a rack; and an object of my invention is to provide a lever mechanism of the class just described in which the position of the lever may be adjusted with great nicety.

Another object of my invention is to provide a lever mechanism of this class which will be simple in construction, cheap in manufacture and efficient in operation.

In the drawings illustrating the principle of my invention and the best mode now known to me of applying that principle, Figure 1 is an elevation showing one of the pawls engaged; Fig. 2 is a similar view showing both of the pawls disengaged; and Fig. 3 is a section on the line A—A of Fig. 1.

In the base of the support *a* is fulcrumed the lever *b* to which is riveted or otherwise suitably secured a casing *c*, in which are slidably mounted the pawls *d*, the lower ends *e* of which rub together, while the upper ends *f* are separated and are formed with the holes *g*. Between the upper ends *g* is interposed a toothed segment *h* formed with an ear *i* to which is pivotally secured the latch link-rod *j* and one end of the coil-spring *k*, the other end of which is secured to a boss *m* formed upon the lower part of the casing *c*. The upper portion of the support *a* is a curved rack-bar *n*. While it has not been shown in the drawing, it will be understood that the upper end of the link-rod *j* is pivotally secured to an ordinary thumb-latch by which the link-rod *j* may be raised against the tension of the coil-spring *k*.

The parts being in the position shown in Fig. 1, and it being desired to move the lever a distance equivalent to one half the interval between two adjacent teeth *o* of the rack *n*, the link-rod *j* is pulled upwardly against the tension of the coil-spring *k* thereby rotating the toothed segment *h* to the left in the figures. The teeth *p* of the left-hand side of the

segment play in the holes *g* of the left-hand pawl; and since this pawl rests upon the top of one of the teeth *o*, it remains stationary. The toothed segment *h* acts as a lever, the fulcrum of which is the upper end of the left-hand pawl; and the teeth on the right-hand half of the toothed segment, by their engagement in the holes in the upper end of the right-hand pawl, raise that pawl from between the teeth *o* of the rack *n*. The lever *b* may now be shifted in either direction. When the lower end of one of the pawls passes from the top of the tooth *o*, the coil-spring *k* will immediately force that pawl into the notch between the teeth *o*, it being understood that the operator releases the link-rod *j* so that it may be pulled down.

The casing and its contained pawls, toothed segment and spring may be made separately and in different sizes and attached to the ordinary lever now in use upon farm machinery throughout the country, from which it will appear that my new mechanism has a wide field of usefulness.

I claim:

1. In a lever mechanism of the class described, the combination with a lever and a rack for holding said lever in position, of a pair of coöperating slideable pawls carried by said lever, the lower ends of said pawls being adapted to rub against each other and to engage alternately said rack and the upper ends of said pawls being separated; a device interposed between said upper ends and in engagement therewith; yielding means one end of which is secured to said device and the other end of which is secured to said lever; and means for moving said device to raise one of said pawls against the tension of said yielding means.

2. In a lever mechanism of the class described, the combination with a lever and a rack for holding said lever in position, of a pair of coöperating slideable pawls carried by said lever, the lower ends of said pawls being adapted to engage alternately said rack; a toothed device interposed between and in mesh with the upper ends of said pawls; yielding means one end of which is secured to said device and the other end of which is secured to said lever; and means for throwing said toothed device to raise one of said pawls against the tension of said yielding means.

3. In a lever mechanism of the character

described the combination of a casing; a pair of coöoperating pawls, the lower ends of which are adapted to rub together and the upper ends of which are separated; and a device for moving said pawls, said device being interposed between said upper ends and in engagement therewith.

In witness whereof I have hereunto set my

hand in the presence of the two undersigned witnesses at said Stacyville this 20th day of May, 1907.

FRANK A. FALK.
